UNITED STATES PATENT OFFICE.

SUSAN ELIZABETH BARNEY, OF NEW YORK, N. Y.

DESIGN FOR A MATCH-SAFE.

SPECIFICATION forming part of Design No. 81,741, dated October 31, 1899.

Application filed October 5, 1899. Serial No. 732,724. Term of patent 3½ years.

To all whom it may concern:

Be it known that I, SUSAN ELIZABETH BARNEY, a citizen of the United States, residing at New York, (Kingsbridge,) in the county of New York and State of New York, have invented and produced a new and original Design for Match-Safes, of which the following is a specification, reference being had to the accompanying drawing, forming part thereof.

5 Referring to the drawing, the leading or material feature of my design consists of a horse 2, provided with a saddle 3 and with a saddle-bag 4, arranged at either side of the horse and basket-shaped in form and having bale-shaped handles or supports 5.

Having fully described my invention, I claim as new and desire to secure by Letters Patent—

The design for a match-safe, substantially as shown and described.

In testimony that I claim the foregoing as my invention I have signed my name, in presence of the subscribing witnesses, this 3d day of October, 1899.
